UNITED STATES PATENT OFFICE.

GUIDO SEMENZA, OF MILAN, ITALY.

HIGH-TENSION INSULATOR.

No. 905,940.

Specification of Letters Patent.

Patented Dec. 8, 1908.

Application filed February 5, 1906. Serial No. 299,588.

To all whom it may concern:

Be it known that I, GUIDO SEMENZA, electrical engineer, subject of the King of Italy, residing at 4 Via Palestro, Milan, Italy, 5 have invented certain new and useful Improvements in High-Tension Insulators; and I do hereby declare the following to be a full, clear, and exact description of the invention, such as will enable others skilled in the art to 10 which it appertains to make and use the same.

The chief point to be kept in view in designing insulators for very high voltages is to avoid superficial disruptive discharges, especially when the insulators are exposed to 15 heavy rains. The outer petticoat, on the top of which the conductor is secured, extends outwardly to a considerable extent to protect from water the smaller and lower 20 petticoats. When the upper petticoat has got wet, its tension is the same as that of the conductor, wherefore its upper surface is quite inefficient from the point of view of insulation. Moreover the water drops, falling 25 down from the upper petticoat, when succeeding each other at short intervals, offer an easy path to the disruptive discharges between the edge of the petticoat itself and the supporting pin or the cross arm. For the 30 above reason high tension insulators usually are very large and very difficult to manufacture so much the more that the upper petticoats must, in spite of the size be made with the utmost care in order to resist disruptive 35 breakdown or puncture.

According to the present invention, the different tasks are accomplished by different parts of the insulator and the troubles, depending upon the rain, are obviated so as to 40 afford an insulator the efficiency of which, against external disruptive discharges, is almost as high in wet as in dry weather. This result is attained by making the insulator of 45 two distinct parts; the lower one namely the insulator proper is intended to support the conductor and does not require any outwardly extending upper petticoat; the upper part, which is termed the cap, is secured 50 above the insulator proper and may be formed of any insulating material whatever as it is only intended to protect the lower petticoats of the insulator proper from rain, rendering the water drops dripping from said upper cap innocuous.

Figures 1 and 2 show, by way of example 55 only, two manners of carrying out my invention.

In both figures the upper cap of umbrella 1 made of porcelain, glass or any other convenient material, is fitted with two gutters 2, 60 situated at the ends of the same diameter and preventing the water drops from directly falling on the conductor or wire 7. The lower edge of the cap must be so shaped as to facilitate the vertical falling of the drops; in the 65 example shown by the drawings the lower face of the cap consists in a plan having a sharp cutting outer edge.

The cap is secured to the top of the insulator proper by means of a threaded spigot 5 70 entering a socket 4 correspondingly threaded, with which the cap is provided; but the connection between the cap and the insulator proper may be obtained by any other convenient means (cements and the like). 75

The insulator proper may be formed either of one or several pieces of any shape whatever. The uppermost petticoats of the insulator proper must be much smaller in diameter than the cap in order that the protection 80 against the rain, afforded by the latter, may prove an efficient one.

According to Fig. 1 the spigot shaped top 5 of the insulator proper is fitted with screw threads for securing the cap thereto; a lower 85 circular recess 6 is intended to receive the conductor 7, if it is to be tied to the insulator laterally; the petticoats 8 may be more or less in number and have any convenient shape according to the circumstances. According to Fig. 2 the top 5 is fitted with a central recess 9 wherein the conductor 7 rests, in the case of central tying being resorted to. 90

The inspection of the figures show:

(1) That the cap has no insulating function, so as to allow of its being composed of a material of low dielectric rigidity while its size, even if very large, does not give rise to special difficulties of manufacture as it is the case with the large petticoat insulators now 100 in use.

(2) That the water dripping from the cap does not come into contact with the conductor and does not therefore render the superficial disruptive discharges easier. 105

(3) That the gutters (2) prevent the water from the cap to drip on the conductor. The latter therefore only receives the direct rain,

which owing to the conductor having a certain sag, follows the same up to a certain extent before leaving it.

(4.) That the petticoats (8) situated below the cap are completely protected thereby and will therefore remain dry.

All in all the insulator proper may henceforth be made much smaller and its manufacture will prove much easier and cheaper than it is the case with the present types.

The insulators proper will have to be fitted on their supporting pins without the respective caps which will be only mounted after the complete erection of the transmission line.

Now what I claim is:

1. In a high tension insulator, the combination, with a conductor and a conductor-carrier of insulating material having a portion projecting above the conductor, of a cap of insulating material secured to the conductor-carrier and out of contact with the conductor, said cap extending over the conductor-carrier.

2. A high tension insulator, having a top section with wide flat rim, a lower wide flat rim section at a considerable distance from the first, and an intermediate distance piece connecting the other two sections.

3. A high tension insulator having a top section with wide flat rim, a lower wide flat rim section at a considerable distance from the first, and an intermediate socket and spigot distance piece between the two.

4. A high tension insulator having a top section with wide flat rim, a lower wide rim section at a considerable distance from the first, an intermediate distance piece of socket and spigot construction, and a flaring petticoat section below the second wide rim section.

In testimony whereof I affix my signature to this specification, in the presence of two witnesses.

GUIDO SEMENZA.
